UNITED STATES PATENT OFFICE

2,493,695

HOISTING TOWER

Ralph V. Payne, Washington, D. C.

Application September 9, 1946, Serial No. 695,728

1 Claim. (Cl. 187—2)

1.

The invention relates to a hoisting tower set-up, and more especially to a quick-erecting and knock-down hoisting tower or temporary elevator.

The primary object of this invention is the provision of a tower of this character, wherein a vertically movable workmen's platform and small stifflegged derrick is arranged so that the same can be raised or lowered, using the power of the engine and in this manner the erection or taking down of the tower eliminates the necessity of workmen subjecting themselves to hazardous climbs as is ordinarily required with hoisting towers now employed on building construction.

A further object of the invention is the provision wherein the construction is novel in form so that when in the knock-down condition, it can be conveniently and easily transported to the location required for its service, and can also be erected using the stiff-legged derrick to hoist long prefabricated sections of the tower into place with the power of the engine.

A still further object of the invention is the provision of a tower which has the base of the tower and the engine in one compact unit.

With these and other objects in view, the invention consists in the features of construction, combination, and arrangements of parts as will be hereinafter more fully described and illustrated in the accompanying drawings, which disclose one of the many methods which could be used in a tower of this character.

In the accompanying drawings:

Figure 1 is a side elevation of the tower at the stage of erecting the outer panel of the second section of the elevator.

Figure 2 is a front elevation with the first section in position above the stub tower.

Figure 3 is a top plan view of the workmen's platform and diagonal members.

Figure 4 is a perspective view of one of the sections.

Figure 5 is a perspective view of a ledger for connecting the sections in position.

Figure 6 is an elevational view of the elevator.

Figure 7 is a side view thereof, and

Figure 8 is a perspective view of the pulley block.

Referring more in detail to the drawings, the device comprises a suitable base or platform 10 of the required size and length, which has at one end thereof axles 12 journalled in bearings 14, and wheels 16 mounted on the axles 12 permit transportation of the device from one location to another. The opposite end of the base 10 is

2

provided with a lift 18 by which the unmounted end may be steered and controlled.

Fixed at one end of the base 10 are the vertical corner posts 20, and fixed to the sides of the base 10 and relatively spaced from the corner posts are similar posts 22. These posts form the lowermost section of a tower, elevator or scaffold. The posts are supported by the diagonal braces 21 fixed to the upper ends of the posts 20 and extending to the base as shown, and the diagonal braces 23 are fixed to the upper ends of the posts 22 and to the center of the opposed posts parallel thereto as shown. Horizontal braces 25 also tend to strengthen the structure.

Fixed to the corner posts 20 and 22 are the prefabricated sections 24 shown in Figure 4, having the vertical channel iron members 26, transverse channel iron members 28 and diagonal members 30. Intermediate the members 26 and centrally thereof are the vertical track members 32 for the platform of the elevator 34, which travels within the sections. The elevator 34 is provided with opposed guides 35 which are positioned to travel on opposite track members 32 to guide the elevator in its ascent and descent.

The members 26 are provided with keyhole slots 36 which are adapted to receive the headed pins 38 of the transverse channel beams 40, the pins of which are welded to the upper and lower edges thereof. The beams are positioned in the members 26 by means of the pins 38 in horizontal relationship with the members 28, and pivoted latches 42 mounted on the members 28 by pins 44, engage the ends of the beams 40 and retain them in fixed relation to the sections 24. The beams 40 can be connected at various other points temporarily, but in the position previously described, they are securely connected to the sections 24.

The corner posts and sections 24 being constructed of channel iron, are welded in fixed relation to each other, and when the members 26 of the sections abut each other during the construction of the tower, the members 28 are welded to the top of the lower section of the members 26, as shown in Figure 4, but are not connected to the lower ends of the upper sections. By thus employing the required number of sections 24 and beams 40, the tower may be built to any desired height upon the base 10 by the fastening of such section and beams as previously described.

Arranged for vertical travel within the scaffold or tower, between the corner posts and sections, is the elevator or workmen's platform 34. Fixed to the elevator 34 centrally thereof is the

stiff-leg derrick 45, comprising the mast 46, which is provided with the diagonal brace 48 for the strengthening thereof. Pivottally connected to the apertured eared collar 50 at the base of the derrick mast 46 is the boom 52 having the hand operated boom control winch 54 secured thereto. The cable 56 of the winch is trained through the pulley 58 secured to the apertured eared collar 60 at the upper end of the derrick mast 46 and the pulley 62 on the end of the boom 52 and secured at its free end to the pulley 58, thus the winch 54 will manually raise the boom as desired.

Secured to the lower or under side of the elevator 34 by means of uprights 64 is the frame 66 on which is mounted the pulley block 68 in which is mounted pulleys 70, 71, 73 and 75 respectively.

Mounted on the end of the base 10, opposite the corner posts and tower is a motor 72 having the drive pulley 74 which has power connection with a pulley 75 mounted in bearings 76 on the base 10, the pulley 75 is provided with a gear 78 which meshes with the gears 80 and 82 respectively, that are mounted on the shafts 84 and 86 of the cable drums 88 and 90 respectively. The drums are mounted by means of bearings 92 and 94 on the drum supports 96 and 98 on the base 10, and the drums are controlled by dogs 99 pivoted on the base 101 of the supports 96 and 98.

At the stage of erection shown in Figure 1, the cable 100 from drum 88 is trained under the pulley 102, which is fixed to the supporting members 30 centrally of the corner posts 22 and extends upwardly of the tower to be trained over the pulley 106 from where it extends under the elevator 34 under pulleys 71 and 75, then upwardly of the tower to be fixed at a dead end to the section 24 which is already fixed in position on the opposite side of the elevator.

When it is desired to hoist another section into position, the cable 108 of the drum 90 is trained under the pulley 110 fixed to the member 30 adjacent pulley 102 over pulley 70 on the elevator 34 under pulley 73 over pulley 114 on the boom 52 at the base thereof and pulley 104 at the upper end thereof to be connected to the member 28 of the section 24 which is to be hoisted in position. When the section has been positioned, the beams 40 are connected as previously described.

A material platform 116 is provided which ascends and descends in the space, immediately below the elevator 34, and within the corner posts.

After the sections 24 have been elevated to the desired height, and the elevator 34 elevated to the next section the elevator is held in position by diagonal blocks 118 under the elevator 34 and positioned diagonally across the corners of the members 28 and beams 40.

Each of the units 24 is elevated, as illustrated in Figure 1, with the motor through the cable 108 which is trained around the pulleys 110, 70, 73, 114 and 104 and with the ends secured to the cross member 28 of the unit and after the unit is elevated to its position upon one of the posts 20 or 22 of the base section of the frame it is secured in position by the beams 40 at the sides and supported by diagonal bracing. With the sections or units 24 at the front and rear of the elevator installed in position the cable 100 which is trained around the pulleys 102, 106, 71 and 75 and anchored to the cross beam 28 at the upper end of a unit on the opposite side of the elevator, is wound on the drum and with the pulley 106 elevated to the upper position with the installation of the section 24, the elevator 34 may be elevated to a

position above the upper beams 28, the pulley block arrangement 68 being suspended below the elevator platform, and the diagonal blocks 118 may be inserted under the corners of the elevator platform.

The stiff-leg 45 is then in position to elevate two more of the units or sections 24 with the cross beams and braces associated therewith. This cycle of operations may be continued whereby an elevator of any suitable height may be temporarily constructed.

The cable 100 may be disconnected from its respective prefabricated sections and trained downwardly through the pulleys 71 and 75 in the block 68 to be connected to the platform 116. The platform 116 is hoisted and lowered in the conventional manner, using the same track members as the elevator 34. If any material is too long to be accommodated on the material platform, the derrick can be used to hoist the same.

As stated, the elevator is held in position by the diagonal blocks 118, but these can be eliminated if desired and the elevator can be bolted to the prefabricated sections.

The tower can be dismantled by reversing the previously described operations, but the base and the posts fixed thereto are permanent, and the elevator and material platform remain in lowered positions when the tower is not in use or is to be transported from one location to another.

The prefabricated sections remain assembled as described whereby the erection and dismantling of the tower can be accomplished at a greater speed in less time and more efficiently.

Every part of the tower, including guy wires, beams and other braces, can be hoisted by the engine, and this method of erection is a variation of the same mechanical principle that is used by steel erectors in moving up derricks when erecting steel frame work buildings.

It is believed that the construction and operation of the device will be apparent to those skilled in the art, and that it is to be understood that changes may be made in the details of construction, arrangement and combination of parts without departing from the spirit of the invention and the scope of the appended claim.

Having thus described the invention what is claimed as new and desired to be secured by Letters Patent is:

In a temporary elevator structure for building construction, the combination which comprises a base frame including a platform with four corner posts extended upwardly therefrom and supported by diagonal braces, a motor positioned on the platform, a plurality of drums mounted on the platform, means actuating the drums by the motor, said posts having keyhole slots in the side surfaces and positioned at the upper ends thereof, a plurality of units having posts connected by cross beams and diagonal braces with the posts thereof positioned to stand on the upper ends of the posts of the platform, said posts of the units having keyhole slots in the side surfaces thereof, connecting cross beams having headed studs thereon with the studs positioned to enter the keyhole slots of the posts for interlocking the lower ends of the posts of the units to the upper ends of supporting posts, an elevator platform positioned between the posts of the units, blocks diagonally positioned across the corners of the units for supporting the elevator platform, a stiff-leg derrick having a boom with a winch thereon carried by the elevator platform, an elongated pulley block suspended from the elevator plat-

form, a plurality of pulleys in the pulley block and on the elevator structure, a unit hoisting cable extended from a drum of the motor over pulleys in the pulley block and on the boom for attachment to a unit of the structure for elevating the unit, and an elevator hoisting cable extended from another drum of the motor and trained over a pulley in a unit positioned on one side of the structure, around pulleys of the pulley block of the elevator and to an anchoring point in the upper end of a unit on the opposite of the structure whereby as force is applied to the cable the cable elevates the elevator platform with the derrick thereon to a new position.
